[57] CLAIM

The ornamental design for an infant's safety seat, as shown and described.

DESCRIPTION

FIG. 1 is a front perspective view of an infant's safety seat showing my new design;

FIG. 2 is a side elevational view;

FIG. 3 is a front elevational view; and

FIG. 4 is a rear elevational view thereof on a reduced scale.

The side of the seat not shown is a mirror image of the side shown in FIG. 2.

FIG. 4

FIG. 1

FIG. 2

FIG. 3
